FISH LURE

William W. Multanen, Santa Cruz, Calif.

Application November 25, 1957, Serial No. 48,631

Term of patent 14 years

(Cl. D31—4)

Fig. 1.

Fig. 2.

Fig. 3.

Fig. 4.

Fig. 1 is a side elevational view of a fish lure showing my new design. When the lure is rotated on its longitudinal axis 180° from the position illustrated in Fig. 1, the lure exhibits the same ornamental appearance as is seen in Fig. 1.

Fig. 2 is top plan view of my fish lure as seen from a position with the lure rotated 90° on its longitudinal axis from the position of Fig. 1. When the lure is rotated on its longitudinal axis 180° from the position illustrated in Fig. 2, the lure exhibits the same ornamental appearance as is seen in Fig. 2.

Fig. 3 is front end elevational view of Fig. 2.
Fig. 4 is a rear end elevational view of Fig. 2.

I claim:

The ornamental design for a fish lure, as shown and described.
